MEMBRANE PUMP

Friedrich Wilhelm Pleuger, Juthornstrasse 80, Hamburg-Wandsbek, Germany, and Johann Schneider, Hamburg-Wandsbek, Germany; said Schneider, assignor to said Pleuger

Filed July 8, 1958, Ser. No. 747,191

Claims priority, application Germany July 17, 1957

15 Claims. (Cl. 103—152)

This invention relates to pumps and is especially concerned with submersible deep well pumps of the type wherein a flexible pumping membrane divides a pumping chamber from a working chamber filled with hydraulic fluid and wherein the membrane is flexed by alternately increasing and reducing the pressure of the hydraulic fluid in the working chamber.

Membrane pumps of the character just described are now known to the art but, when pumping highly viscous liquids, they occasionally do not work satisfactorily under conditions where the pumping membrane is flexed too rapidly to give the highly viscous liquids sufficient time in which to enter the pumping chamber.

The principal object of the present invention is to overcome the difficulty just mentioned, and we accomplish this purpose by providing an auxiliary pump which is placed between the working chamber and a reservoir containing hydraulic fluid, which pump is maintained in continual operation so as to constantly deliver hydraulic fluid to the working chamber. At the same time we provide a valve system for controlling the movements of the pumping membrane, so that, when a predetermined membrane displacement has been effected, especially the maximum displacement, communication will be established between the working chamber and an outlet to the reservoir which communication is maintained until the pressure of the hydraulic fluid is sufficiently reduced to enable the pumping membrane to return to its initial or starting position. The displacement of the auxiliary pump is designed to be considerably less than that of the pumping membrane and we provide for operating the valve system either directly by the membrane movement or indirectly through a contacting system actuated by the pumping membrane, or through a separate impulse generator.

An additional feature of the invention is the provision of a snap spring system between the valve body of the valve system and a valve body actuating member, which spring system is arranged to be effective in both directions of actuation. The springs of the snap spring system are designed so that they cannot overcome the break-loose friction between the valve housing and the valve body until a certain predetermined tension is reached.

According to a modification of the invention we also provide holding magnets by means of which the action of the snap spring system of the valve mechanism may be intensified so that the valve body may be held firmly in its extreme positions with a force, however, which does not exceed the maximum valve actuating force.

How the foregoing objects and advantages together with certain additional objects and advantages which will be referred to later are attained will now be described in connection with the accompanying drawings which illustrate somewhat schematically two preferred embodiments of the invention.

Figure 1 of the drawings illustrates a heavy oil submersible pump in axial longitudinal section with portions of the mechanical drive and the suction and discharge passages omitted.

2

Figure 2 is a cross section on a somewhat enlarged scale taken approximately as indicated by the line 2—2 on Figure 3.

Figure 3 is an axial section similar to that of Figure 1, but illustrating the center portion only of a pump embodying a variation of the invention.

In the embodiment of Figure 1, a composite cylindrical body is contained in a pump casing 1 said body being composed of three sections 2, 3 and 4 which are secured to one another by means of axially disposed bolts 5. The bolts 5 pass through axial holes bored in the middle body section 3 and are screwed into a threaded hole in body section 2 and secured by nuts 6 in a recess in body section 4.

Body section 2 surrounds the pumping chamber 7 which chamber is connected in a well known manner to a suction chamber 9 by means of a suction valve 8 and to a discharge line (not illustrated) by means of a check valve 10. The suction chamber 9 communicates through a strainer-like portion 11 of the pump casing 1 with the liquid to be pumped, generally the heavy oil contained in a well.

A pumping membrane 12 preferably in the form of a bellows membrane, as shown, is clamped between body sections 2 and 3. This bellows membrane 12 can be inflated by means of an auxiliary pump to be described below. This serves to reduce the volume of the pumping chamber 7 and thereby forces the liquid contained therein to flow out through the check or foot valve 10. To this end it will be understood, of course, that the suction valve 8 acts as a check valve during the pumping stroke of the bellows in a manner well understood in this art.

The driving mechanism for the membrane pump is housed in the lower portion of the pump casing 1 and it comprises an electrical motor (not shown) which motor is disposed concentrically within the pump casing. The shaft 14 of the motor is mounted in ball bearings 13 and carries a beveled driving gear 15. The ball bearing 13 and the electrical motor are housed in a body section 16 which is likewise fastened in the pump casing. Between body sections 4 and 16 an eccentric shaft 17 is mounted in tapered roller bearings 18, the shaft 17 being driven by the bevel gear 15 through the medium of bevel gear 19.

A tappet 21 rests upon eccentric 20 of the shafts 17 and can be displaced axially in a sleeve 22 in body section 4 and the piston 23 of an auxiliary pump rests upon the tappet 21. To reduce the friction a bearing ball 24 is arranged between tappet 21 and piston 23. The auxiliary pump cylinder 25 forms part of an inserted piece 26 which latter is placed in an axial central hole bored in the body section 3. The location of inserted piece 26 is fixed by means of a bushing 27 at the top, which bushing abuts an inwardly projecting shoulder 3a on the body section 3. This construction forms the housing for a slide valve which is to be described below. To support the insert 26 at the bottom, an additional bushing 28 is used, the lower extremity of which rests upon sleeve 22.

In order to keep piston 23 and bearing ball 24 in constant contact with tappet 21, a compression coil spring 29 is used, one end of which abuts against inserted piece 26 and the other end against a collar-like portion 23a formed at the bottom of piston 23. Piston 23 may be provided in the ordinary manner with piston rings 30.

The auxiliary pumping chamber 31, defined by piston 23 and cylinder 25, communicates through an axial passage 32 with a slide valve to be described below. In this passage or hole 32 there is a ball check valve 33 which prevents back flow to auxiliary pumping chamber 31 during the suction stroke. Movement of the check valve ball 33 is limited by a perforated fitting 34 which is screwed into a suitable aperture in passage 32.

The auxiliary pumping chamber 31 furthermore communicates through radial passages 35 and annular channel 36 in inserted piece 26 with a radially directed passage 37 bored in body section 3. Passage 37 is closed at its outside end with a threaded plug 38, and communicates with a reservoir 41 through a pipe 43 which passes around bearing 18 of eccentric shaft 17 and terminates in a check valve 40 in body section 16. Check valve 40, like check valve 33, is fastened in place by a threaded fitting 42.

Above the axial passage 32 a slide valve is mounted within the housing sleeve 27, said slide valve consisting of an external sleeve 44 and an internal sleeve 45. The external sleeve 44 forms the actual valve and this slides within the housing sleeve 27 in intimate contact therewith. In its extreme lower position as shown in Figure 1 the sleeve 44 closes port 47 of radially directed outlet passage 46 in body section 3. In its extreme upper position the slide valve 44 uncovers said port 47 thereby providing communication between the passage 32 and the outlet passage 46.

As already mentioned, an internal valve sleeve 45 is provided within the external sleeve 44. This internal sleeve has one or more axially orientated passageways 45a (see Figure 2) formed by the spaced projections 45b on the internal sleeve 45. The axial passage 32 communicates through the passageways 45a with the working chamber 48 enclosed by the bellows membrane 12. Compression springs 51 and 52 are inserted between the projections 45b on the internal sleeve 45 and snap rings 49 and 50 inserted into the inside wall of external sleeve 44. These springs are constructed and arranged to hold the two intersliding valve sleeves 44 and 45 in a central or middle position. Indeed, if the bellows membrane 12 is capable of an especially long stroke, springs 51 and 52 may be supported at first at one end only so as not to bear against the internal sleeve 45 until the latter travels the desired longer distance. The inner sleeve 45 is firmly fastened to the bellows membrane 12 by the valve actuating rod 53 which thus constitutes an actual physical connection between the bellows membrane and the valve. To avoid binding of the slide valve, the lower end of the valve actuating rod 53 is provided with a ball 54 adapted to fit into the center bore of internal sleeve 45. This ball abuts on one side against an annular internal shoulder 55 and on the other side against a set screw 56 screwed into the sleeve. This construction creates a sort of universal joint between the valve actuating rod 53 and the slide valve which functions to compensate for possible errors of alignment.

The radially directed outlet passage 46 is sealed at its outside end by a threaded plug 57 and communicates through an axial passage 58 in the body section 3 with the hydraulic reservoir 41 which reservoir also contains the motor and the transmission. The suction check valve 40-42 is beneath the normal oil level in the reservoir as shown in Figure 1, the minimum oil level being shown by a dot and dash line marked with the legend. However, the outlet for discharge passage 47-46-58 may empty into the reservoir 41 at a point above the oil level as indicated in Figure 1.

The operation of the modification of our invention so far described is as follows: Assuming first that the pump is a submersible pump and has been lowered into an oil well and that the pump motor has been started and is rotating. The rotation of the motor is transmitted through the bevel gears 15 and 19, to the eccentric shaft 17 and eccentric 20, thus causing tappet 21 to be repeatedly lifted and dropped. This up-and-down movement of tappet 21 is transferred through ball 24 to pump piston 23 which constantly aspirates hydraulic fluid out of reservoir 41 through suction check valve 40-42 and passages 43-39-37. As mentioned previously, the reservoir is filled with hydraulic fluid at least to such an extent that

the bottom end of pipe 43 remains constantly immersed in the hydraulic fluid. Upon each compression stroke of pump piston 23, the hydraulic fluid is pumped out of auxiliary pumping chamber 31, through check valve 33-34 and the axial passageways 45a in the internal slide valve sleeve 45, into the working chamber 48. Membrane 12 thus inflates and extends upward to reduce the volume of pumping chamber 7.

Since the displacement of pump piston 23 is quite 10 considerably smaller than the displacement of bellows membrane 12, a relatively large number of strokes of auxiliary pump 23-25 are required before bellows membrane 12 will be inflated to its maximum extension. In this maximum extension of bellows membrane 12, the 15 internal sleeve 45 of the slide valve is lifted upward by valve actuating rod 53, relatively to the external sleeve 44. The external sleeve 44 is at first held by friction in the slide valve casing 27. But as soon as the compression spring 51 is sufficiently compressed by the relative movement of the two valve sleeves 44 and 45 that its force 20 exceeds the friction force between the external sleeve 44 and slide valve casing 27, the slide valve jumps quite suddenly into its opposite extreme position.

In its opposite extreme position, the external valve 25 sleeve 44 uncovers port 47 in slide valve casing 27, so that the hydraulic fluid contained in working chamber 48 can flow out through passages 46 and 58 into the reservoir 41. The collapsing of the bellows membrane is favored 30 by the pressure of the liquid flowing into pumping chamber 7.

In the downward travel of bellows membrane 12, valve 35 actuating rod 53 pushes the internal valve sleeve 45 downward. At first the external sleeve 44 is held in its upper extreme position by friction. As valve actuating rod 53 moves downward, spring 52 is compressed until it finally 40 develops sufficient power to overcome the friction which holds the external valve sleeve in its upper extreme position and the slide valve will suddenly spring into the other extreme position. In this position, outlet passage 46 is again closed, so that membrane 12 can again be inflated for the next pumping stroke. It must also be mentioned that, during the entire return or suction stroke of bellows membrane 12, the auxiliary pump 23-25 is pumping hydraulic fluid out of reservoir 41 into passage 45 32. This hydraulic fluid, however, immediately flows back to reservoir 41 through passages 46 and 58 during the suction stroke of the membrane.

In the slow up-and-down movements of bellows membrane 12, the viscous liquid being handled is let in through 50 suction valve 8 and pumped through foot valve 10 into the discharge pipe.

As will be appreciated the pump 23-25 will function satisfactorily only when the interior of membrane 12 is always supplied with oil arriving from chamber 41 via 55 valve 40 and passages 39, 37, 32 and 45a. Since this oil comes from the reservoir 41, a vacuum will develop unless an overpressure is present in the reservoir. In order to prevent this, membrane 12 is initially inflated with hydraulic fluid while the reservoir is exposed to atmospheric pressure. Then return of fluid to the reservoir 60 will increase the air pressure in the reservoir so that at no time will a vacuum exist in the system.

Another possibility for preventing the formation of a 65 vacuum in the reservoir 41 consists in pumping air into the reservoir so that a compressed air cushion is developed therein. However, under normal operation, heating of the oil by the motor suffices to achieve the desired pressurization of the reservoir. In the event that no air cushion is provided in the reservoir and the reservoir is 70 completely filled with oil, an equalizing membrane or membranes of adequate size must be associated with the motor and to this end the wall of the housing 1 adjacent to the reservoir 41 is formed with a flexible diaphragm or diaphragms subject on the inside to the pressure of the hydraulic fluid within the chamber 41 and on the other 75

side to the pressure of the oil in the well. Such diaphragms will compensate for variations in the volume of hydraulic fluid in the chamber 41 by flexing toward the reservoir as the oil is pumped to the membrane 12 and back again as the oil returns to the reservoir.

In the modification illustrated in Figure 3 the principle of operation is essentially the same as that of the embodiment shown in Figure 1. For this reason the parts which have the same function in the two embodiments are marked with the same reference characters. The embodiment of Figure 3 differs from that of Figure 1 mainly in the following respect. After the bellows membrane 12 is inflated and an outlet passageway to the reservoir 41 opened up the piston pump 23-25 is also used to pump the hydraulic fluid back out of the working chamber 48 into the reservoir. In this embodiment the slide valve is actuated as before by the valve actuating rod 53 but the hydraulic fluid after passing through the axial passageway 32 is fed through radial passages 58 and an annular passage 59 in inserted piece 26 and a radially directed hole 60 in body section 3. Hole 60 communicates with an axial passage 61 which in turn communicates through two connecting passages 62 and 63 with the inside of the slide valve casing 27. The outlet passage 46, which is connected with slide valve casing port 47, also communicates with passages 35 through a passage 64 and check valve 40'. An additional outlet passage is formed by a radial bore 65 which communicates with reservoir 41 through the axial passage 66. A recess 67 is provided in the outer sleeve 44 of the slide valve, which can connect outlet passage 65 with inlet passage 63-61.

The pump system according to Figures 2 and 3 operates as follows:

The pump piston is constantly moved up and down, the same as in the first-described embodiment. Hydraulic fluid is thus aspirated through check valve 40' and passage 46 from reservoir 41, and is discharged through passages 32, 58, 61 and 62 into the working chamber 48. The membrane is inflated and the slide valve actuated in the same manner as in the case of the first-described embodiment. As soon as the slide valve has switched into the opposite position, the external valve sleeve 44 blocks the inlet port 62, so that no more hydraulic fluid can be pumped into working chamber 48. Port 47 is simultaneously uncovered, so that the hydraulic fluid can flow out of working chamber 48, through passages 46 and 58. However—and this is the essential difference from the embodiment in Figure 1—the hydraulic fluid is positively pumped out of working chamber 48. Recess 67 in external valve sleeve 44 connects the discharge line 61 of auxiliary pump 23-25 directly to the outlet passage 65. Since the check valve 40' is opposite outlet port 47, the auxiliary pump 23-25 now sucks the hydraulic fluid out through port 47, so that working chamber 48 is emptied very rapidly.

In order to make the action of the slide valve as sudden as possible, the external valve sleeve 44 can also be slotted, in order to increase the ratio between the break-loose friction and the sliding friction between slide valve casing 27 and external valve sleeve 44. An additional possibility of holding the slide valve in its end positions consists in using special holding magnets 68 and 69, as shown in Figure 3.

By modifying the rate of flow of the auxiliary pump, the size of the membrane displacement, the flow resistances in the outlet passages etc., the operation of the membrane can be varied and controlled within wide limits.

The invention is by no means limited to the embodiment described, and a system can be designed in like manner using other kinds of pumps, as for example radially operating piston pumps. Of course, pumps with

a plurality of pistons can also be used. The controlling system represented in the drawings and described above represents only one of the many possibilities for the control of the membrane flexion. Instead of a sleeve-type slide valve control, the outlet ports can be opened or closed in like manner by the rotation of a piston. A toggle lever-type snap valve is also conceivable. In certain cases it may also be expedient to provide an electrical control in which the membrane then merely actuates contacts which control the flow by means of electromagnets or electric motors.

A further possibility of the invention consists in controlling the membrane pump with an impulse generator (e.g., rotary magnets) which controls the valve movement with a very precise, adjustable rhythm. If such an impulse generator is electrically operated, it can be controlled either through a second cable or through the motor cable. The membrane stroke is made longer or shorter by slower or more rapid operation of the slide valve while the auxiliary pump output remains the same, so that the rate of flow of the heavy oil pump can be adjusted within wide limits without other changes. If an impulse generator is used, provision can be made by means of a valve coupled to the membrane so that safety relief ports are opened if the membrane is excessively inflated. In this manner, damage to the membrane or bellows can be prevented in case of improper operation or failure of the impulse generator, etc.

In conclusion, we wish to point out that by our improvement we can completely overcome the difficulties sometimes encountered where the liquid to be pumped is of a very heavy viscous nature. By employing an auxiliary pump as shown and described together with a suitable valve control mechanism therefor it is possible to effect actuation or flexure of the pumping membrane with whatever degree of rapidity or slowness may be necessary with relation to the viscosity of the liquid being pumped from the well. With structures heretofore in use, as previously pointed out, the flexure of the membrane was too rapid to give the highly viscous liquids sufficient time to enter the pumping chamber, but with the improvements disclosed herein this difficulty can be overcome in the manner described. Furthermore, the valve system which we have adopted is so designed that it connects the discharge line of the auxiliary pump to the outlet to the reservoir during the suction stroke of the pumping membrane. In this manner the return movement of the membrane which is normally initiated by the incoming pressure of the liquid being pumped is accelerated.

50 We claim:

1. A submersible deep well pump comprising a housing containing a pumping chamber, a working chamber, a flexible pumping membrane separating said chambers, hydraulic operating fluid in the working chamber, a hydraulic fluid reservoir, an auxiliary pump having a discharge line delivering hydraulic operating fluid from the reservoir to the working chamber whereby to increase the pressure in the latter and effect flexure of the membrane in its pumping direction, the displacement of the auxiliary pump being substantially less than the displacement of the pumping membrane, a hydraulic fluid return line from the working chamber to the reservoir, a valve controlling the flow of fluid through said return line, and means adapted to move said valve to permit return of fluid from the working chamber to the reservoir upon a predetermined degree of flexure of the pumping membrane in its pumping direction whereby to reduce the hydraulic pressure in the working chamber and thereby to permit the pumping membrane to return to its starting position.

2. A pump according to claim 1 characterized by the fact that the means for moving the valve which controls the fluid return line includes a physical connection between the pumping membrane and the valve whereby movement of the membrane is directly transmitted to the valve.

3. A pump according to claim 2 wherein the said valve is a friction slide valve mounted to move in a suitable bore and, further, wherein the connection between the membrane and the valve includes a snap spring means so constructed and arranged as to delay movement of the valve until the spring means has been tensed sufficiently to overcome the break-loose friction between the valve and its bore.

4. A membrane pump according to claim 2 wherein the valve is a slide valve arranged coaxially with the axis of membrane movement and wherein the connection includes a member articulated in the center of the pumping membrane.

5. A membrane pump according to claim 3 wherein the slide valve is arranged in a passageway which extends from the auxiliary pump to the working chamber and, further, wherein the slide valve is provided with axially disposed passageways through which the hydraulic fluid is pumped from the reservoir to the working chamber.

6. A membrane pump according to claim 3 wherein the valve is a slide valve comprising two relatively movable sleeves, one within the other, with the inner one connected to the membrane and arranged to transfer its axial displacements through the spring means to the other.

7. A membrane pump according to claim 2 wherein holding magnets are provided which are adapted to hold the valve in its extreme positions with a holding force not exceeding the maximum valve actuating force.

8. A membrane pump according to claim 1 characterized by the fact that the discharge line of the auxiliary pump is connected to the reservoir during the suction stroke of the pumping membrane.

9. A membrane pump according to claim 8 wherein the auxiliary pump draws hydraulic fluid out of the working chamber during the suction stroke of the membrane.

10. A membrane pump according to claim 1 wherein the membrane is of the bellows type.

11. A membrane pump according to claim 1 wherein the motor and driving means for the auxiliary pump are housed in the reservoir.

5 12. A membrane pump according to claim 1 characterized by the fact that the pumping chamber, the pumping membrane, the valve, the auxiliary pump and the driving means for the latter are aligned axially with one another and one above the other in a common housing for all.

10 13. A pump according to claim 1 wherein the auxiliary pump is a piston and cylinder pump and wherein is provided a passageway for connecting the cylinder with the reservoir and another passageway for connecting the cylinder with the working chamber together with a check valve in each passageway.

15 14. A pump according to claim 13 characterized by the fact that a motor is provided for driving the piston of the auxiliary pump and that said motor delivers its power to the piston through a tappet actuated by an eccentric driven by the motor and, further, that a bearing ball is provided between the piston and the tappet and a spring for maintaining contact between the ball and the tappet and between the ball and the piston.

20 15. A submersible, deep-well, pump comprising an elongated housing containing a well pumping chamber having intake and discharge connections, a working chamber, a bellows membrane separating said chambers, an auxiliary pump, a hydraulic fluid reservoir, motor means for actuating the auxiliary pump, a connection between the reservoir and the working chamber through which the auxiliary pump is adapted to deliver hydraulic fluid from the reservoir to the working chamber, a connection for returning hydraulic fluid from the working chamber to the reservoir, a valve for controlling said return connection, said valve being adapted to close the hydraulic fluid return connection until the bellows is flexed toward the pumping chamber a desired predetermined amount, and means controlled by the bellows membrane for moving said valve to open the return connection when the auxiliary pump has increased the pressure in the working chamber sufficiently to flex the bellows membrane as described.
